UNITED STATES PATENT OFFICE.

FRANK KENYON, OF WASHINGTON, DISTRICT OF COLUMBIA.

COMBINED COLLAR AND NECKTIE CLASP.

SPECIFICATION forming part of Letters Patent No. 642,459, dated January 30, 1900.

Application filed June 24, 1899. Serial No. 721,765. (No model.)

To all whom it may concern:

Be it known that I, FRANK KENYON, a citizen of the United States, residing at Washington, in the District of Columbia, have invented certain new and useful Improvements in a Combined Collar and Necktie Clasp; and I do hereby declare the following to be a full, clear, and exact description of the invention, such as will enable others skilled in the art to which it appertains to make and use the same.

My invention relates to a combined collar and necktie clasp.

The object of the invention is to produce a simple and ingenious clasp for preventing the accidental derangement of the collar or necktie.

To the accomplishment of this object the invention consists in forming a clasp of two pivoted or hinged members, one of which is provided with an opening for the reception of the head of the collar-button and the other of which is provided with a prong designed for the double purpose of urging the first-named member into its proper position and engaging the tie to retain it in place, the two members being retained in their wide-open or closed positions by an interposed spring.

Referring to the drawings, Figure 1 is a general view showing the application of my invention. Fig. 2 is a perspective view of the device in the open position. Fig. 3 is a side elevation showing the prong in contact with the lower edge of the button-head and in the act of forcing the upper portion of the slotted member behind the button-head. Fig. 4 is a similar view with the device positioned as in use. Fig. 5 is a detail perspective view of one of the members, and Fig. 6 is a similar view of the other member.

Referring to the numerals of reference on the drawings, 1 and 2 indicate the hinged members of my clasp. The member 1 comprises a sheet-metal plate provided with a pair of ears 3 and 4, bent from the plate into parallel relation and between which is located a spring-tongue 5, cut from the plate and bent down parallel to the face thereof, the opening 6, formed by the cutting out of the tongue, being designed for the reception of the head of the collar-button—as, for instance, the button employed for the purpose of retaining the rear ends of the collar-band and

which passes through the buttonhole at the rear of the collar. The slot or opening 5 is preferably formed, as shown, with a broad base and a gradually-diminishing width toward its upper end. The purpose of this particular form of slot or opening is to permit the passage of the collar-button head therethrough and to prevent its ready withdrawal after the member has been drawn down until the upper end of the opening or slot is occupied by the stem of the collar-button, in which position the head of the button overlaps the edges of the opening.

The member 2 is of less length than the member 1 in order that its upper edge 7, which is slightly concave, may pass under the head of the collar-button when the clasp is in place. It is slightly wider at its upper end than the adjacent portion of the member 1 in order that it may be readily grasped between the fingers, and it is provided adjacent to its lower end with parallel ears 8 and 9, which are imposed against the ears 3 and 4 of the member 1, the contiguous oppositely-extending ears upon the members being pivotally united by pintles 10 and 11 of any desired form.

The numeral 12 indicates a lug or flange formed by bending the lower end of the member 2 at right angles thereto and into contact with the spring-tongue 5 of the member 1.

It will be seen from this description that when the member 2 is swung back into the wide-open position the lug 12 will lie flat against the tongue, and the spring action of the latter will serve to hold the member 2 in the open position, as the direction of pressure is substantially in line with the pintles. It will be equally obvious, however, that when the member 2 is swung forward slightly the edge of the lug or flange 12 will travel toward the extremity of the tongue, gradually causing the tongue to exert its spring-pressure upon the section 2 below the pintles, at which time the spring-pressure will be utilized to close the member 2 against the member 1 and to retain it in that position.

This clasp is designed not only for the purpose of retaining a tie, but to prevent the accidental passage of the collar-button through the hole in the collar, which would effect the release of the latter. It is therefore essen-

tial that the upper portion of the member 1 should be drawn down snugly between the button-head and collar and upon the stem or shank of the button. I therefore cut a triangular slit in the member 2 adjacent to its upper edge and bend back the triangular piece thus defined to form a prong 13, which is designed to engage the band of the tie passing between the members and to contact with the lower edge of the button in case the member 1 has not been drawn down snugly. Slight pressure applied to the member 2 will cause the prong, which is slightly inclined, to be forced under the button, thereby necessarily drawing down the member 1 upon the shank of the collar-button and simultaneously securing the button in the collar and the clasp upon the button, the upper edge of the member 2 being finally slipped under the head of the button. It will now be seen that as the head of the collar-button overlaps the edges of the slot in the member 1 and the upper edge of the member 2 the button cannot be accidentally withdrawn from the collar nor can the clasp be accidentally removed from the button, and as the prong will pass through the material of the tie, or, rather, through the band thereof, passing around the neck of the wearer and between the members, said tie will be held securely against derangement in any direction until it is desired to remove it, the entire device being released by grasping the upper edge of the member 2 between the fingers and throwing it back to the open position, when, as will be obvious, the tie may be removed and the clasp dislodged from the button by simply moving it upward sufficiently to allow the head of the collar-button to pass through the wide end of the opening.

40 While the present embodiment of my invention is believed to be preferable, I do not

desire to limit myself to the structural details illustrated and described, but reserve the right to make such changes, variations, and modifications as may come properly within the scope of the protection prayed.

What I claim is—

1. A clasp of the character described comprising a pair of hinged members, one of said members being provided with a spring-tongue 50 cut from the member to form an elongated opening for the reception of a button-head and bent back over the face of the member, the other of said members being provided with a projection across its lower extremity 55 and in operative contact with the extremity of the spring-tongue, substantially as specified.

2. In a clasp, the combination with a sheet-metal member provided with a pair of ears 60 adjacent to one end, an elongated slot comparatively narrow at its upper end and with a spring-tongue formed from the metal of the member and bent back over the face of the member below the slot and between the ears, 65 of a second member of less length and greater width than the first-named member and provided with parallel ears adjacent to one end pivotally connected with the ears of the other member, said second member being also provided at its lower end with a right-angular projection and with a prong extending from its inner face adjacent to its upper edge and inclined with respect to the face of the second member, substantially as specified.

In testimony whereof I affix my signature in presence of two witnesses.

FRANK KENYON.
